US00D785735S

(12) United States Design Patent (10) Patent No.: US D785,735 S
(45) Date of Patent:  May 2, 2017

(54) GOLF CLUB HEAD

(71) Applicant: Karsten Manufacturing Corporation,
Phoenix, AZ (US)

(72) Inventors: Cory Bacon, Phoenix, AZ (US); Ryan Stokke, Phoenix, AZ (US); Martin Jertson, Phoenix, AZ (US); Xiaojian Chen, Phoenix, AZ (US); Daniel Lee, Phoenix, AZ (US)

(73) Assignee: Karsten Manufacturing Corporation,
Phoenix, AZ (US)

() Term: 15 Years

(21) Appl. No.: 29/540,205

(22) Filed: Sep. 22, 2015

(51) LOC (10) Cl. 21-02

(52) U.S. Cl.

USPC D21/752

(58) Field of Classification Search

USPC D21/759, 752

CPC A63B 53/04; A63B 53/0466; A63B 2053/002; A63B 2053/0445; A63B 2053/0433; A63B 2053/0437; A63B 2053/0491

Primary Examiner — Mitchell Siegel

(57) CLAIM

The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a front view of the golf club head of FIG. 1; FIG. 4 is a rear view of the golf club head of FIG. 1; FIG. 5 is a top view of the golf club head of FIG. 1;

FIG. 6 is a bottom view of the golf club head of FIG. 1; FIG. 7 is a left view of the golf club head of FIG. 1; and, FIG. 8 is a right view of the golf club head of FIG. 1. The broken lines shown in one or more of the figures are for illustrative purposes only and form no part of the claimed design.

1 Claim, 4 Drawing Sheets
